UNITED STATES PATENT OFFICE.

ESTEY MURRELL TURNER, OF PASADENA, CALIFORNIA.

INTERNAL-COMBUSTION ENGINE.

931,976.

Specification of Letters Patent. Patented Aug. 24, 1909.

Application filed August 10, 1908. Serial No. 447,849.

To all whom it may concern:

Be it known that I, ESTEY MURRELL TURNER, a citizen of the United States, residing at Pasadena, in the county of Los Angeles 5 and State of California, have invented a new and useful Internal-Combustion Engine, of which the following is a specification.

This invention relates to internal combustion engines and more specially to a type of 10 internal combustion engines pertaining to what is commonly known as a four cycle engine.

One of the principal objects of the invention is to provide an improved general construction of such an engine wherein main and secondary compression chambers are used.

Another object of the invention is to provide, in such an engine, an air compression chamber wherein air, free from hydro-carbon, receives a preliminary compression, together with a secondary compression chamber wherein the explosive mixture of air and hydro-carbon is compressed.

A further object of the invention is to provide an improved mixing valve between the primary or air-compressing chamber and the secondary or mixture compressing chamber.

A still further object of the invention is to provide an improved means of actuating the inlet and exhaust valves common to such engines, wherein the operating parts or cams are held in closed chambers capable of being filled with lubricants.

With the above and other objects in view as will become hereinafter apparent, the invention consists in general of a cylinder wherein is mounted a reciprocating piston, a crank case held at the lower or front end of 35 said cylinder and closed with the exception of valved inlet and outlet ports, said crank case acting as an air-compressing chamber, valved inlet and outlet ports to the back end of said cylinder, a secondary compression 40 chamber extending from the outlet port of the crank case to the inlet port of the cylinder proper, an improved mixing valve held between the primary and secondary compressing chambers, closed cam chambers 45 formed on the sides of said crank case, valve rods connected to the inlet and outlet valves of the cylinder and extending within said cam chambers, and cams held in said cam chambers to actuate said inlet and outlet 50 valves.

The invention further consists in certain

novel details of construction and combination of parts, hereinafter fully described, illustrated in the accompanying drawings, and specifically set forth in the claims. 60

In the accompanying drawings, like characters of reference indicate like parts in the several views, and:—Figure 1 is a transverse section through an engine constructed in accordance with this invention. Fig. 2 is a 65 partial side elevation showing the gearing actuating the cam shaft. Fig. 3 is a horizontal section on the line "A—B" of Fig. 1. Fig. 4 is a detailed section through the mixing valve. 70

The numeral 10 indicates the cylinder of the engine wherein is mounted a piston 11, of the type usual in internal combustion engines. Upon the lower or front end of the cylinder 10 is held a crank case 12 provided 75 with suitable bearings 13 for the shaft 14. These bearings are preferably provided with stuffing boxes of any ordinary form, in order to make the crank case air-tight. With the crank-case 12 is the crank 16, and 80

a piston rod or pitman 17, serves to connect the crank 16 with the piston 11. The upper or back end of the cylinder is provided with two laterally disposed chambers whereof 18 forms an exhaust passage and 19 forms an 85 inlet passage. Valve-seats 20 are formed in each of these chambers and an exhaust valve 21 is held to close the exhaust passage 18, while a similar valve 22 is held to close the inlet passage 19. The chambers 18 and 19 90

are each provided with openings 23, disposed opposite the valve seat 20 and of such size that the valves 21 and 22 may be removed therethrough. These openings 23 are each provided with a suitable closure 24, preferably in the form of a screw-threaded plug. The exhaust passage 18 is continued below the valve seat 20 to form an auxiliary exhaust passage 25 and in like manner the inlet passage 19 is continued downward to 100 form a passage 26, which latter passage acts as an extension of the secondary compression chamber, hereafter to be described. The passage 25 freely communicates with the atmosphere through a suitable port 27. 105 Valve stems 28 are connected to the valves 21 and 22 and extend downward through guides or bearings 29, formed integrally with the bottom walls of the passages 25 and 26. These valve stems 28 terminate a short distance below the lower or forward ends of the guides 29. 110

On the exterior of the crank case 12, and in alinement with the chambers 18 and 19 is formed a pair of chambers 30. Each of these chambers 30 is provided in the side walls with bearings 31, through which pass cam shafts 32 having cams 33 mounted thereon. These chambers are further provided with open sides which are normally closed by means of cover plates 34. In the upper or rear ends of each of these chambers is an opening 35, wherein is held a guide 36, having a lift rod 37 slidably mounted therein in alinement with the valve stems 28. These lift rods 37 are provided each with a wiper foot 38, arranged to lie in the paths of the cams 33. In order to actuate these cams there is provided on the shaft 14 a gear 39 and on each of the shafts 32 a gear 40, the latter being of twice the diameter of the gear 39, so that two revolutions of the shaft 14 cause but one revolution of each of the shafts 32.

It is to be noted that the lift rod 37 and the valve stems 28 have their ends in juxtaposition but are not in any way connected, this arrangement being adopted in order that the various parts may be disassembled without disturbing other parts not requiring renewal or repair.

The crank case 12 is provided with an opening 41 in one side thereof, wherein is positioned a valve casing 42, carrying a valve 43, arranged to open inwardly. The valve casing 42 is provided with a valve stem guide 44 wherein moves a valve stem 45 connected to the valve 43. A spring 46 is held upon the outer end of the valve stem and serves to normally hold the inlet port formed by the valve casing closed. A second opening 47 is formed in the crank-case 12, and in this opening is positioned a valve casing 48. A valve seat 49 is formed in this valve casing and adjacent the valve seat is a channel 50, provided with a plurality of apertures 51, leading from the channel to the valve seat. A suitable pipe connection 52 is provided on this valve casing and has a port 53 communicating with the channel 50. Upon this connection 52 is mounted a pipe, not deemed necessary here to be shown, which in turn communicates with a suitable source of hydro-carbon supply, also omitted from the drawings as being immaterial to the correct understanding of the invention. A valve 54, provided with a stem 55, moving in a guide 56, is held within this valve casing and opens outwardly from the crank case 12. A spring 57 normally serves to hold the valve 54 upon the seat 49 and close the port formed by the valve casing as well as the apertures 51 leading from the channel 50.

The chamber 26, above referred to, is provided with a port 58; and an auxiliary or explosive mixture compression chamber 59 is connected to the port 58 and to the valve

casing 48 by means of suitable unions 60, or such other connection as may be deemed most advisable for the purpose.

It is to be noted that the crank case 12 may have an explosive mixture admitted thereto through the valve 43 and the same may be then enriched by added hydro-carbon, admitted through the apertures 51, or the crank case 12 may be utilized solely for the purpose of compressing air before admitting any of the hydro-carbon. In either case it is to be observed that the explosive mixture may be regulated to a nicety.

In the operation of the invention let it be assumed that the piston is moving on the working stroke, or toward the lower or front end of the cylinder. This downward movement compresses the air in the crank case and forces it through the valve casing 48, at the same time slightly closing the valve 43. As the air rushes through the valve casing 48 it passes around the valve 54 and carries with it into the chamber 59 a certain amount of hydro-carbon which is thoroughly mixed with the air by reason of the numerous apertures 51 leading from the channel 50. In the meantime, as the pressure on the upper side of the valve 22 is greater than that on the lower side, the valve 22 remains closed, and the charge undergoes a preliminary compression in the chamber 59. Upon the completion of the downward movement of the piston it starts backward and at the same time the cam 33 actuating the exhaust valve 31 opens this valve and the exhaust gases are swept out through the chamber 18 and the passage 25. Simultaneously with this operation the valve 43 opens by reason of the suction caused by the piston moving upward, and the valve 54 is closed. A fresh charge of air is thus drawn into the crank case 12. Upon the next forward stroke of the piston or suction stroke, the cam 33 of the exhaust valve will have revolved sufficiently to permit this valve to again seat itself, and the cam 33 of the inlet valve 22 will have revolved to open said inlet valve. The compressed explosive mixture in the chamber 59 is thus permitted to enter the combustion chamber at the upper end or rear of the cylinder, and at the same time the air in the crank case 12 is forced through the valve casing 14 and an added charge of the explosive mixture is forced into the combustion chamber. Upon the next upstroke of the piston, or what is known as the compression stroke, the charge admitted through the valve 22 is compressed and fired in any of the usual manners, and the cycle begins again.

It is obvious that many minor changes may be made in the form and construction of the invention without departing from the material principles thereof. It is not therefore desired to confine the invention to the

exact form herein shown and described, but it is wished to include all such as properly come within the scope thereof.

Having thus described the invention, what is claimed as new is:

- 5 1. In an internal combustion engine, a cylinder provided with a combustion chamber having valved inlet and outlet ports, a piston held to reciprocate in said cylinder, a

10 crank case at the end of said cylinder forming a primary compression chamber and provided with inlet and outlet ports, a secondary compression chamber connected to the outlet port of the crank case and the inlet

15 port of the cylinder, and a full inlet to said secondary compression chamber.
2. In an internal combustion engine, a cylinder provided with a combustion chamber having inlet and exhaust ports, valves

20 controlling said inlet and exhaust ports, a crank shaft, a pair of cam shafts, gears connecting said crank shaft and cam shaft, a cam on each of said crank shafts to actuate the aforesaid valve, means actuated by

25 said cams to open said inlet and exhaust valves, a crank case at the end of said cylinder, forming a primary compression chamber, and provided with inlet and outlet ports, spring-closed valves for said inlet and outlet

30 ports, a secondary compression chamber connected to the outlet port of the crank case and the inlet port of the cylinder, and means controlled by the outlet valve of said crank case to admit the hydrocarbon through

35 the secondary compression chamber.
3. In an internal combustion engine, a cylinder provided with a combustion chamber having valved inlet and exhaust ports, a piston held to reciprocate in said cylinder, a

40 crank case at the end of said cylinder forming a primary compression chamber and provided with inlet and outlet ports, a secondary compression chamber connected to the outlet port of the crank case and the inlet

45 port of the cylinder, a spring-closed inlet

valve, controlling the inlet port of the crank case, a valve seat formed in the outlet port of the said crank case provided with a hydro-carbon channel formed in the body of the chamber around said valve seat and having a

50 plurality of apertures opening therethrough, a spring-closed outlet valve arranged to close said outlet port and apertures, and mechanical means to actuate the inlet and exhaust valves of the combustion chamber.

4. In an internal combustion engine, a cylinder provided with a combustion chamber having valved inlet and exhaust ports, a piston held to reciprocate in said cylinder, a

55 crank case at the end of said cylinder, forming a primary compression chamber and provided with inlet and outlet ports, a secondary compression chamber connected to the outlet port of the crank case and the inlet

60 port of the cylinder, a spring-closed inlet valve controlling the inlet port of the crank case, a valve seat formed in the outlet port of said crank case provided with a hydro-carbon channel formed in the body of the chamber around said valve seat having a

65 plurality of apertures opening thereto, a spring-closed outlet valve arranged to close said outlet port and apertures, a crank shaft, a pair of cam chambers, a cam shaft carrying a cam held in each of said cam chambers,

70 valve stems connected to the inlet and exhaust valves of said cylinder, lift rods held in alinement with said valve stems and passing into said cam chambers, and gears on said cam shaft and crank shaft to actuate

75 said cams and control the inlet and exhaust valves of said cylinder.

In testimony that I claim the foregoing as my own, I have hereto affixed my signature in the presence of two witnesses.

ESTEY MURRELL TURNER.
